(57) **CLAIM**

The ornamental design for a contact lens case, as shown and described.

DESCRIPTION

FIG. 1 is a front view of a contact lens case design showing my new design.

FIG. 2 is a rear view thereof.

FIG. 3 is a left side view thereof.

FIG. 4 is a right side view thereof.

FIG. 5 is a top view thereof.

FIG. 6 is a bottom view thereof.

FIG. 7 is a front left perspective view thereof.

FIG. 8 is a top left perspective view thereof.

FIG. 9 is a perspective view of a contact lens case, with the fitting stick and tweezers removed; and,

FIG. 10 is a perspective view of the contact lens case in its closed state.

Any shading and cross-hatching are not features of the design but are utilized to illustrate the surface contours of the contact lens case in the drawings. The dotted lines in the figure views show portions of the contact lens case that form no part of the claimed design.
